CLAIM

The ornamental design for a building controller, as shown and described.

DESCRIPTION

FIG. 1 is a perspective view of a building controller; FIG. 2 is a front elevation view of the building controller of FIG. 1; FIGS. 3-6 are left, right, top and bottom views, respectively, of the building controller of FIG. 1; FIG. 7 is a perspective view of another building controller; FIG. 8 is a front elevation view of the building controller of FIG. 7; FIGS. 9-12 are left, right, top and bottom views, respectively, of the building controller of FIG. 7; FIG. 13 is a perspective view of yet another building controller; FIG. 14 is a front elevation view of the building controller of FIG. 13; and, FIGS. 15-18 are left, right, top and bottom views, respectively, of the building controller of FIG. 13. In the drawings, the claimed design is defined by the shaded surfaces; broken lines immediately adjacent shaded surfaces represent boundaries of the claim and form no part thereof; all other broken lines depict unclaimed environmental subject matter and form no part of the claim.
